UNITED STATES PATENT OFFICE.

BENJAMIN SKIDMORE, JR., OF CHICAGO, ILLINOIS.

CONDENSER AND VACUUM PUMP.

Application filed January 20, 1921. Serial No. 438,595.

To all whom it may concern:

Be it known that I, BENJAMIN SKIDMORE, Jr., a citizen of the United States, residing at Chicago, in the county of Cook and State 5 of Illinois, have invented certain new and useful Improvement in Condensers and Vacuum Pumps, of which the following is a specification.

This invention relates to improvements in 10 condenser and vacuum pump and one of the objects of the same is to provide an improved simple and efficient apparatus of this character, particularly adapted, though not necessarily limited in its use with a steam 15 turbine and when so employed may be directly coupled to the shaft of the steam turbine.

To the attainment of these ends and the 20 accomplishment of other new and useful objects as will appear, the invention consists in the features of novelty in substantially the construction, combination and arrangement of the several parts hereinafter more fully described and claimed and shown in the 25 accompanying drawing illustrating this invention and in which—

Figure 1 is a vertical sectional view taken on line 1—1 Figure 2.

Figure 2 is a vertical sectional view taken 30 on line 2—2, Figure 1.

Figure 3 is a view similar to Figure 2 of a modified form of the invention.

Referring more particularly to the drawing 35 the numeral 10, designates a shaft which is rotated in any desired or suitable manner. This shaft is journaled in suitable bearings 11, carried by a supporting base 12.

Connected with the shaft 10, to rotate 40 therewith is a rotor 13, which may be of any desired diameter and consists of a plurality of blades 14, which are preferably spaced from the axis of rotation. The outer extremities of the blades 14, terminate adjacent the periphery of the rotor to form circumferential spaces therebetween to freely 45 admit the liquid adjacent the periphery of the rotor. The extremities of the blades adjacent the periphery of the rotor are preferably deflected as at 15, in the direction 50 of rotation of the rotor.

The rotor is arranged within a suitable casing 16, having an inlet opening 17, and a discharge outlet passage 18.

The casing 16, is of an internal diameter 55 considerably larger than the external diameter of the rotor and interposed between the

rotor and the wall of the casing and spaced from each are a series of angularly disposed stationary blades 19, having passages 20 therebetween. These blades 19, form a 60 chamber or passage 21, between the blades and the wall of the casing 16, and also a chamber or passage 22, disposed between the blades 19, and the periphery of the rotor 13, and which chambers or passages have 65 communication with each other through the passages 20.

The casing 16, is also provided with an inlet opening 23, for the steam or vapor to be condensed and also for other fluids, and 70 this inlet 23, delivers the fluids to the rotor adjacent the center or axis of rotation thereof, and within the blades 14.

If desired suitable packing such as labyrinth rings 24, may be provided between 75 the rotor 13, and the wall of the casing to form a fluid tight joint.

The shaft 10, passes through the walls of the casing 16, and suitable stuffing boxes 25— 80 26, are arranged around the shaft adjacent the points where it passes through the walls of the casing to form fluid tight joints.

In operation and when employed as a condenser, the steam or vapor enters the inlet 85 23, and the water or cooling fluid enters the casing through the inlet 17. The cooling fluid fills the passage 21, and then flows through the passage ways 20, between the blades 19, and into the passageway 22.

As the rotor 13, operates, the blades 14, 90 will throw any liquid by centrifugal force from the rotor into the space or passageway 22, between the rotor and the blades 19, and in so doing together with the effect of the stationary blades 19, the liquid will be 95 broken up and form a spray in the passage 22, thereby forming or creating a large condensing area and entraining any air that is delivered to the rotor, the liquid and air being finally discharged with considerable 100 force through the discharge passageway 18.

When the apparatus is used as a vacuum pump solely, air or other gases enter the 105 rotor through the inlet passage 23, and are then entrained by the action of the blades 14, and the stationary blades 19, on the liquid, the liquid and entrained gases being then discharged through the discharge outlet passage 18, thereby causing a partial vacuum or suction in the passageway 23.

The angularly disposed blades 14, render it possible to discharge the liquid rapidly

from the rotor with a minimum amount of shock, and by deflecting the extremities 15, of the blades 14, in the direction of rotation of the rotor, the deflected ends of the 5 blades operate to spray the liquid.

This apparatus may be connected with the return line of a steam heating system by connecting the line at the inlet opening 23, of the casing 16, and when so employed, 10 it is particularly advantageous in that should there be any steam or vapor in the return line it will be immediately condensed by the apparatus.

In Figure 3 there is shown a modified or 15 double form of apparatus embodying a casing 27, having an inlet 28, and discharge outlets 29—30. Within this casing are arranged two series of stationary blades 31—32, the blades 31, being spaced to form 20 passages 33, therebetween, the blades 32, form passages 34, therebetween.

These two series of blades 31—32 are arranged within the casing opposite each other and on opposite sides of the rotor 25 and the blades are respectively spaced from the rotor and the wall of the casing to form passages 35—36, between the blades and the wall of the casing and passages 37—38, between the respective series of blades and 30 the periphery of the rotor, the passages 37 communicating with the discharge outlet passage 30, and the passage 38, communicating with the discharge outlet passage 29.

The operation of this form of the invention 35 is the same as that shown in Figure 2, with the exception that the liquid which enters the inlet 28, passes to opposite sides of the rotor and is delivered through the respective passages 33—34 to the rotor and 40 from the casing is delivered from the respective passages 37—38 through the respective discharge outlet passages 30—29.

While the preferred forms of the invention have been herein shown and described 45 it is to be understood that various changes may be made in the details of construction and in the combination and arrangement of the several parts, within the scope of the claims, without departing from the spirit of 50 this invention.

What is claimed as new is:—

1. An apparatus of the character described embodying a casing having an inlet for liquid and an outlet, a rotor in the casing 55 and of a diameter smaller than the interior of the casing to form a space therebetween, a plurality of spaced stationary blades arranged intermediate the casing and the rotor and dividing the casing into two passages 60 having communication with each other between adjacent blades, said casing having an inlet for delivering fluid to the rotor, the said rotor blades being circumferentially spaced at the periphery of the rotor to operate upon 65 the liquid adjacent the periphery of the

rotor to form a spray of the liquid, thereby creating a large condensing area for the vapor delivered to the rotor.

2. An apparatus of the character described embodying a casing having an inlet for liquid and an outlet, a rotor in the casing and of a diameter considerably smaller than the interior of the casing, a plurality of spaced stationary blades arranged intermediate the casing and the rotor and dividing the casing into two passages having communication with each other between adjacent blades, said casing having an inlet for delivering vapor to the rotor, the said rotor blades operating upon the liquid in the adjacent passages to form a spray of the liquid therein thereby creating a large condensing area for the vapor delivered to the rotor, the said passages between the said stationary blades discharging in the direction of rotation of the rotor and in a general direction towards the rotor. 75

3. An apparatus of the character described embodying a casing having an inlet for liquid and an outlet, a rotor in the casing and of a diameter smaller than the interior of the casing to form a space between the casing and the periphery of the rotor, a plurality of spaced stationary blades arranged intermediate the casing and the rotor and dividing the casing into two passages having communication with each other between adjacent blades, said casing having an inlet for delivering fluid to the rotor, the said rotor blades being circumferentially spaced at the periphery of the rotor to operate upon the liquid adjacent the periphery of the rotor to form a spray of the liquid, thereby creating a large condensing area for the vapor delivered to the rotor, the ends of the rotor blades adjacent the periphery thereof having a slight forward deflection 100 in the direction of rotation of the rotor. 90

4. An apparatus of the character described embodying a casing having an inlet for the liquid adapted to deliver the liquid so that it surrounds the periphery of the rotor, and an outlet, a rotor in the casing, there being an inlet to the casing for delivering fluid to the rotor in proximity to the axis of rotation thereof, and means whereby the rotor 110 will operate upon the liquid which surrounds the periphery thereof to break up or cause such liquid to form a spray adjacent the periphery of the rotor to create a large condensing area for the fluid delivered to the rotor. 115

5. An apparatus of the character described embodying a casing having an inlet for the liquid adapted to deliver the liquid so that it surrounds the periphery of the rotor, and an outlet, and a rotor in the casing, said rotor embodying circumferentially spaced blades to form unobstructed spaces at the 125 periphery of the rotor, there being an inlet 130

to the casing for delivering fluid to the rotor in proximity to the axis of rotation of the rotor, the liquid surrounding the rotor being admitted into the said spaces in a general direction from the periphery of the rotor inwardly, the said blades operating upon the liquid adjacent the periphery of the rotor to break up or cause such liquid to form a spray adjacent the rotor.

6. An apparatus of the character described embodying a casing having an inlet for liquid and an outlet, a rotor in the casing, blades carried by the rotor, and spaced stationary blades interposed between the rotor and the casing wall and spaced from both, there being an inlet to the casing for delivering fluid to the rotor, the action of the rotor blades and the said stationary blades upon the liquid operating to entrain the fluid between the stationary blades from the exterior of the rotor toward and in the general direction of rotation of the rotor.

7. An apparatus of the character described embodying a casing having an inlet for liquid and an outlet, a rotor in the casing, 25 blades carried by the rotor, and spaced stationary blades interposed between the rotor and the casing wall and spaced from both, there being an inlet to the casing for delivering fluid to the rotor, the action of 30 the rotor blades and the said stationary blades upon the liquid operating to entrain the fluid, from the exterior of the rotor and towards the periphery thereof, the said stationary blades being inclined to the axis of 35 rotation of the rotor to form passages between the blades having their discharge outlet ends directed in the general direction of rotation of the rotor.

In testimony whereof I have signed my 40 name to this specification on this 10th day of January, A. D. 1921.

BENJAMIN SKIDMORE, JR.
